UNITED STATES PATENT OFFICE.

NELSON H. STURGIS AND MATHEW S. ALLEN, OF GUTHRIE, OKLAHOMA TERRITORY.

MAIL-BOX.

SPECIFICATION forming part of Letters Patent No. 757,513, dated April 19, 1904.

Application filed August 23, 1902. Serial No. 120,850. (No model.)

To all whom it may concern:

Be it known that we, NELSON H. STURGIS and MATHEW S. ALLEN, citizens of the United States, residing at Guthrie, in the county of 5 Logan and Territory of Oklahoma, have invented a new and useful Mail-Box, of which the following is a specification.

This invention relates to mail-boxes, and more particularly to that class employed in the 10 rural free-delivery service.

One of the objects of the invention is to provide indicating mechanism of a simple nature and easily operable which will impart desirable information of various sorts—as, for 15 instance, notifying the collector of the presence of mail in the box or showing to passers-by the probable state of the weather as prognosticated by the Weather Bureau—this mechanism being so arranged that it can be 20 operated only by authorized persons.

The preferred form of construction is shown in the accompanying drawings and described in the following specification, though it will be understood that various changes may be 25 made from the structure as set forth.

In the drawings, Figure 1 is a perspective view of the improved mail-box. Fig. 2 is a horizontal sectional view through the same. Fig. 3 is a vertical sectional view through the 30 box. Fig. 4 is a perspective view showing the cover opened and a portion of the walls broken away in order to more clearly illustrate the interior arrangements. Fig. 5 is a plan view of one of the indicator-disks.

Similar reference-numerals indicate corresponding parts in all the figures of the drawings.

In the embodiment of the invention shown a receptacle is employed comprising a bottom 40 10, side walls 11, end walls 12, and a cover 13, hinged to one of the side walls, said cover being fastened in its closed position by a suitable lock 14. The ends 12 are double, or, in other words, each comprises spaced walls 12^a, 45 forming therebetween a chamber 15, having an open top and bottom, as illustrated in Figs. 2

and 4. The inner end walls are preferably integral with the side wall, and the outer walls are supplemental, having flanges 16 at their ends, which are riveted or otherwise secured to the 50 sides contiguous to the corners. These outer walls have suitable openings 17, preferably circular in form and arranged in their central upper portions. The receptacle is arranged to be supported upon a post by one or more 55 clips 17^a, which is adapted to embrace said post and has its ends fastened in one of the side walls.

Spindles 18 extend across the chambers 15 and are journaled in the walls 12^a, said spindles projecting entirely through the walls, as shown. The outer ends of these spindles are made angular to receive a suitable operating-key, and they are protected by circular bosses 19. Arranged in the chambers 15 are indicators in the form of disks 20, secured to the spindles and movable across the openings 17. One of these disks is intended for notifying the mail-collector of the presence of mail in the box, and said disk therefore has differently-colored sections 21, which are movable alternately across the opening 17. The other disk is employed as an indicator to impart information regarding the probable state of the weather in the near future, and it is therefore provided with a plurality of signs, as 22, shaped and colored to correspond with the various flags employed by the United States Weather Bureau, these signs being consecutively movable to a position behind the opening 17 when the stem is revolved. The spindles 18 and disks carried thereby are normally held against rotation by means of toothed wheels 23, secured to the inner ends of the spindles, and dogs 24, arranged upon 85 the inner faces of the inner walls 12^a and engaging these toothed wheels. The end of the box or receptacle which carries the Weather Bureau signals above described may also be provided on its exterior face with a field 25, 90 suitably subdivided and having the different points of the compass marked thereon. A

pointer 26, rotatably mounted within this field, is provided with a squared stem 27, adapted to receive a key, by means of which the pointer may be turned to any of said 5 points, and thereby indicate the direction of the wind. A barometer 28 of suitable construction may also be located upon this end of the receptacle.

The interior of the receptacle is subdivided 10 by longitudinal and transverse partitions 29 into letter-receiving compartments 30, said partitions terminating short of the upper edge of the receptacle. A coin-receiving pocket 31 may also be located in one corner of the 15 receptacle, as shown. A slot or opening 32 is formed in the wall of the receptacle directly above one of the compartments 30 and the pocket 31, this opening being normally covered, however, by flaps 33, hinged to the walls 20 by spring-hinges 34, the outer flap being held in inclined position by means of triangular supporting-plates 35, secured to the wall. The cover 13 is preferably arranged at an inclination and not only covers the open top of 25 the receptacle and its compartments, but also the chambers 15. With this construction it will be apparent that the owner may be provided with a key which will permit him to open the receptacle and place mail therein or 30 remove it therefrom. This stem will also fit in the stem to which the collector's indicator is attached, so that by turning the disk the proper color may be brought into sight through the opening, thus notifying the collector of the presence of mail. Should a person not the owner of the box desire to place 35 mail in the same, he can readily do so by raising the outer flap 33 and passing the letters through the opening, thereby pressing back- 40 wardly the inner flap. This mail, it will be noticed, will drop into the compartment 30 directly beneath the opening, whereas the collector will place the mail to be distributed in the other compartment, and thus all will be 45 kept separate. The pocket 31 is designed to receive coin for stamps, registered letters, or money-orders. The large portion of the box can of course be used for large packages, such as newspapers and the like. The collector is 50 also provided with a key which will permit him to open the box and remove therefrom the mail to be collected, as well as deposit therein the mail to be distributed. At the same time he returns his signal back to its cus- 55 tomary position.

It has been the aim of the Department of Agriculture to distribute as widely as possible the prognostications of the Weather Bureau regarding the state of the weather in the near 60 future. To this end reports are usually sent to different offices, including those of the Post-Office Department. The collector may in turn transmit this information further by

means of the mechanism herewith disclosed, and receiving it from a suitable primary indicator arranged at the post-office or his headquarters he can readily move the various signs upon the boxes along his route to correspond with the signals as furnished at headquarters. It will therefore be apparent that a box is provided which is very simple in construction, 65 will constitute a safe receptacle for mail, and will protect it against the weather. The indicating mechanism is also of a very simple character, and at the same time it cannot 70 readily be moved by any but authorized persons. Another advantage resides in the construction of the closures for the opening 32. These closures are entirely independent, the outer one acting as a water-shed, while the 75 inner one completely closes the opening. The arrangement of the compartments within the box is also advantageous, as it allows the mail deposited by the owner to be kept separate from that deposited by the collector. Attention is also invited to the particular construction of the indicator. In the first place it will be observed that the supplemental wall is attached to the outside of the box proper, and the sight-opening is formed in said supplemental wall. The walls of the box are therefore not weakened by such openings, and, moreover, should it be desirable to dispense with either of the signals the outer wall and signal may be removed without affecting the 80 security of the receptacle proper. Moreover, by having the supplemental wall on the outside the compartment formed thereby has an open top and bottom, so that dirt will not collect in said compartment to interfere with the 85 signal. Another advantage resides in the particular arrangement of the indicator-disk and the ratchet or toothed wheel. By having said toothed wheel on the inside of the inner wall the compartment may be made sufficiently 90 narrow to snugly receive the indicator-disk, as illustrated in Fig. 2, and thus said disk can- 95 not buckle or become displaced.

From the foregoing it is thought that the construction, operation, and many advantages 100 of the herein-described invention will be apparent to those skilled in the art without further description, and it will be understood that various changes in the size, proportion, 105 and minor details of construction may be resorted to without departing from the spirit or sacrificing any of the advantages of the invention.

Having thus described our invention, what we claim as new, and desire to secure by Letters 110 Patent, is—

In a mail-box, the combination with a mail-receptacle having an end wall, of a supplemental wall secured to the outer face of the receptacle and having a sight-opening, said 115 supplemental wall extending across and being

spaced from the end wall forming a compartment that is open at its top and bottom, a spindle extending across the compartment and being journaled in the walls, and an indicator-disk located in the compartment and secured to the spindle, said disk coating with the sight-opening of the supplemental wall.

5 In testimony that we claim the foregoing as

our own we have hereto affixed our signatures in the presence of two witnesses.
